STENCILING APPARATUS

Henry Andrew Gattuso, Adams, Mass.

Application September 23, 1946, Serial No. 698,761

5 Claims. (Cl. 101—124)

1

The present invention relates to a stenciling apparatus particularly designed for marking, lettering, or decorating curved surfaces of cylindrical articles or the like, wherein the curved surface of the article is maintained in tangential rolling line contact with the stencil screen, while ink or paint is forced through the stencil by the action of a squeegee.

The primary object of this invention is to provide a simplified and improved apparatus, wherein in cylindrical articles may be rapidly, easily, and efficiently marked as desired, by use of a stencil screen.

Another object of this invention is to provide a novel squeegee assembly offering rigidity and support to the line of rolling contact between the stencil screen and the article being stenciled, and further, providing a means for controlling the quantity of ink or paint to pass through the stencil onto the article, thus enabling the operator to vary the thickness and intensity of the markings on said article.

Another object of this invention is to provide a suitable mechanism for the adjustment and support under the screen of the cylindrical article to be stenciled and further, offering a new means to facilitate the removal of a stenciled article upon completion of the stenciling operation and the positioning of a new article.

Other objects of the present invention will become apparent from the accompanying drawings and the following specification which relate to one embodiment of the present invention. Variations thereof falling within the scope of the appended claims will be apparent to persons skilled in the art.

In the drawings, Figure 1 is a perspective view of a preferred embodiment of the present invention.

Figure 2 is a longitudinal section of the apparatus shown in Figure 1.

Figure 3 is a sectional view taken on line 3—3 of Figure 2 and showing the work in elevated position and in contact with the screen.

Figure 4 is a diagrammatic view showing the squeegee in its vertical position.

Figure 5 is a view similar to Figure 4 showing the squeegee in a slightly tilted position for heavier printing.

Figure 6 is a similar view showing the squeegee in another tilted position for light printing.

The invention herein described, in general, provides an improved stenciling apparatus for the marking of the curved surface of cylindrical objects. The work is placed upon a support, con-

sisting essentially of stationary rollers, such that the curved surface to be marked may be brought in tangential rolling contact with the underside of a silk stenciling screen which forms the bottom-side of an ink trough. As the ink trough is moved in a direction tangential to the curvature of the work, the friction between the screen and the work causes it to rotate on its own axis. A stationary rubber squeegee, bearing on the line of contact between the screen and cylinder, causes the ink to pass through the previously designed portions of the screen and onto the work.

The apparatus consists of a rectangular base 10, upon which is mounted and secured thereto a pair of parallel frame members 11 disposed longitudinally of the machine. On their inner faces the frame members 11 have parallel, horizontal grooved tracks 12 running longitudinally with the frame and substantially coextensive with it but closed at the rear end. These tracks act as both support and guide for the longitudinal movement of the ink trough 13 and screen 27.

The ink trough 13, which may be of wood, is preferably encased within a metal frame 34, which has a removable end plate 40 screwed to the ends of the frame 34 and provided with a handle 41. The longitudinal elements of the frame 34 are shaped to provide the shouldered portions 42 which ride in the groove 12. This arrangement provides for the easy reciprocation of the trough 13 with its screen 27, and also provides for the ready removal and replacement of the trough 13 and screen 27 in the frame 34.

The work supporting assembly is mounted on a rockable plate 14, secured and pivoted to frame members 11 by pivot arm 15 at one end and, being cut away to a two arm fork at the other end, it is supported there by the eccentric oval shaped cams 16, upon which the arms of the fork rest. The raising or lowering of lever arm 17 rotates the eccentric cams 16, thus raising or lowering the entire work supporting assembly as desired. The height to which the supporting assembly will be raised each time is controlled by the catch spring 18 which is fixed at the desired position by the screw 19, adjustable in an elongated slot.

When the cylinder work piece C is in place and ready for printing, it rests upon four collar nuts 21, held in place by set screws 22, two collar nuts on each of two rotating rods 23 mounted transversely to the ink trough 13 and supported by the vertical projections of the right angle brackets 24. These brackets may be moved longitudinally along plate 14 in grooves 25 to adjust the distance between rods 23 to suit varying dia-

ters of different sized cylinders to be inked.

The apparatus, then, is so designed that when lever 17 is up, the entire work supporting assembly is lowered, enabling the operator to mount cylinder C on the four supporting collar nuts 21 which are positioned along rods 23 so that they support the ends of cylinder C. When in the proper position, set screws 22 are tightened, thus rigidly fixing the supporting collars in position. The lateral adjustment of rods 23 by means of right angle brackets 24 and set by bolts 26 in elongated slots 27 enables the operator to adjust the work supporting assembly to suit the diameter of the cylindrical work piece. The lever 17 is then lowered, causing the eccentric cams 16 to rotate and elevate the entire object supporting assembly until cylinder C is firmly pressed against screen 27 of the ink trough.

The squeegee assembly consists of a rubber squeegee 33 rigidly inserted in holder 35. Squeegee holder 35 is in turn positioned in slots 30 of the vertical squeegee standards 28 and vertically adjustable therein to attain the desired pressure of the squeegee against the stencil screen and the contact line of the work piece C. When adjusted to the proper position along slots 30, the squeegee is maintained in position by clamp bolts 31. Bolts 29, one in each of the standards 28 hold the entire squeegee assembly fixed to the frame members 12.

The squeegee assembly also undergoes another adjustment to vary the heaviness of the print or design stenciled on the work C. By loosening bolts 29, which are positioned so that their longitudinal axis normally lies in a vertical plane with the leading edge, or working edge 36 of the rubber squeegee 33, the entire squeegee assembly may be rotated slightly (to the extent of five or ten degrees) about the longitudinal axis of these bolts. When rotated, from an original vertical position, in a clockwise direction, (as viewed in Figure 6) and secured there as a new working position, less ink is forced through the stencil because a smaller area of the working portion of the rubber squeegee is brought to bear upon the stencil screen and the work C than originally, due to the bias cut of the rubber squeegee; however, when rotated in a counter clockwise direction, the opposite is true, resulting in a heavier and more intense marking of work C.

Thus in the operation of this apparatus, ink trough 13 is moved longitudinally rearward along slide tracks 12 until the operator can easily reach and adjust the object supporting assembly. Work C is then positioned on collar nuts 21, and the assembly is adjusted to fit the cylinder. With the work supporting assembly in its lowered position, ink trough 13 is moved outward along tracks 12. The work supporting assembly is then raised until work C presses firmly against screen 27 and squeegee edge 36, the latter serving as the back pressure element for the rolling contact between the screen and work. The ink trough is then moved rearwardly along tracks 12, causing by friction work C to rotate in situ on roller rods 23, thus bringing different portions of the cylinder in contact with different parts of the stencil screen, while squeegee 33 forces ink or paint through the designed parts of the screen onto the cylinder. At this point the work support assembly is lowered by manipulating the lever 17. With the ink trough in its rear position and the work support unit lowered, the work may be removed and a new work piece fed into position. The paint trough is now moved to its for-

ward position, the work support assembly raised and the paint or ink trough moved to its rearward position which results in printing the work piece.

The squeegee 33 is provided with a single beveled face 50 and its lower working edge 36 is substantially in line with the front face of the squeegee. In its normal vertical position the working edge 36 of the squeegee is in firm contact with the screen 27 along a line which is half way between the work supporting rollers 23. With the squeegee in this position, as shown in Figure 4, which is somewhat enlarged, it bears down over the cylindrical workpiece substantially along its diameter. The inclined or beveled face 50 being directly rearwardly, and the motion of the screen 27 being also rearwardly as indicated by the arrow, the very narrow working edge 36 of the squeegee serves to exert pressure upon the work over a relatively limited area through the stenciled portions of the screen 27. When, however, the squeegee is moved only a few degrees to the right, as shown in Figure 5, the edge 36 of the squeegee lies forward of the diameter of the workpiece and the squeegee is more readily responsive to the pressure exerted by the workpiece through the screen with the result that the screen becomes slightly distorted, as shown in Figure 5, and a substantial portion of the beveled face 50 is pressed through the screen and against the work. As a result of this relationship, more ink is trapped by the squeegee and more ink is forced through the screen onto the work. On the contrary, as shown in Figure 6, if the squeegee is moved slightly off-center and rearwardly, then only the linear edge of the working portion of the squeegee is effective and the squeegee offers greater resistance to flattening and a smaller area of the squeegee contacts the screen. Under these conditions less ink will be forced through the screen.

I claim:

1. An apparatus for stenciling cylindrical articles comprising a pair of parallel frame members, a stencil screen carried by the frame members and reciprocable therein, article supporting means disposed below the screen and extending substantially the length of the frame members and pivotally supported by the frame members along a line transversely of the direction of movement of and parallel to the screen, the forward end of the supporting means having lowered and raised positions permitting in its lowered position the removal and feeding of articles, means for raising the forward end of said supporting means for raising an article into firm engagement with the screen and establishing rolling contact therebetween, and a squeegee fixedly supported by said frame members and disposed over the supporting means and serving as a backing for the contact between the article and the screen, the work thereby being always maintained parallel to the screen and the line of contact between the work and screen being thereby subjected to uniform pressure.
2. A stenciling apparatus comprising a pair of parallel frame members, a stencil screen carried by the frame members and reciprocable therein to and from retracted position, article supporting means disposed below the screen and extending substantially the length of the frame members and pivotally supported by the frame members along a line transversely of the direction of movement of and parallel to the screen, the supporting means having at its forward end a pair of

transverse parallel rods, a collar at each end of each rod, a squeegee supported by said frame and disposed over the screen along a median line between said rods, and means for raising and lowering the forward end of said supporting means for raising an article supported by said collars into firm engagement with the screen and pressed against the squeegee and providing for the rotation and printing of said article by the movement of said screen and the action of the squeegee against the screen, the work thereby being always maintained parallel to the screen and the line of contact between the work and screen being thereby subjected to uniform pressure.

3. A stenciling apparatus comprising a pair of parallel frame members each having a guiding channel longitudinally of its inner face, a stencil screen carried by said channels and reciprocable therein to and from retracted position, article supporting means disposed below the screen and extending substantially the length of the frame members and pivotally supported by the frame members along a line transversely of the direction of movement of and parallel to the screen, the supporting means having at its forward end a pair of transverse parallel rods, means for adjusting the distance between said rods, a rotatable collar at each end of each rod adjustable thereon, a squeegee supported by said frame and disposed over the screen along a median line between said rods, and means for raising and lowering the forward end of said supporting means for raising an article supported by said collars into firm engagement with the screen and pressed against the squeegee and providing for the rotation and printing of said article by the movement of said screen and the action of the squeegee against the screen, the work thereby being always maintained parallel to the screen and the line of contact between the work and screen being thereby subjected to uniform pressure.

4. Apparatus for stenciling small cylindrical articles comprising a base, a pair of parallel frame members fixed thereon, a stencil screen carried by the frame member and reciprocable therein to and from retracted position, a work supporting member disposed between the screen and base and extending substantially the length of the apparatus, the rear end of the member being pivotally supported by the frame members along a line transversely of the direction of movement of and parallel to the screen, means for

raising and lowering the forward end of said work supporting member, permitting in its lowered position the feeding and removal of articles and in its raised position bringing the article into firm engagement with said screen and establishing rolling contact therebetween, work supporting means carried by said member, and a squeegee mounted upon said frame members and disposed over said supporting means and serving as a backing for the contact between the article and the screen, the work thereby being always maintained parallel to the screen and squeegee and the line of contact between the work and the screen being thereby subjected to uniform pressure.

15 5. Apparatus for stenciling small cylindrical articles comprising a base, a pair of parallel frame members fixed thereon, a stencil screen carried by the frame members and reciprocable therein to and from retracted position, a work supporting member disposed between the screen and base and extending substantially the length of the apparatus, the rear end of the member being pivotally supported by the frame members along a line transversely of the direction of movement of and parallel to the screen, means for raising and lowering the forward end of said work supporting member, said supporting member carrying supporting means at its forward end comprising adjustably positioned transverse parallel rods, and a squeegee supported by said parallel frame members and disposed over said screen along a median line between said rods, and operating to form a backing for the pressure of the article against said screen, the work thereby being always maintained parallel to the screen and squeegee and the line of contact between the work and the screen being thereby subjected to uniform pressure.
